CASING FOR A THERMOSTAT OR THE LIKE

Earl W. Claus, Kirkwood, Mo., assignor to White-Rodgers Company, St. Louis, Mo., a corporation of Delaware

Application July 22, 1959, Serial No. 56,881

Term of patent 14 years

(Cl. D52—7)

FIG. 2

FIG. 1

FIG. 3

FIG. 4

FIG. 5

Fig. 1 is a front elevation of a casing for a thermostat, showing my new design;

Fig. 2 is a plan view thereof;

Fig. 3 is a right side view thereof;

Fig. 4 is a bottom view thereof; and

Fig. 5 is a view taken on line 5—5 of Fig. 1 showing the sectional contour of the circular knob.

The undisclosed left side view of the thermostat casing is substantially the same as the right side view shown in Fig. 3.

The diamond pattern on the cover panel is embossed.

I claim:

The ornamental design for a casing for a thermostat or the like, substantially as shown and described.
